a dispensed article in a position where it may be viewed by a customer.

A still further object of our invention is to provide an aperture delivery merchandising machine which eliminates the delivery chute customarily employed in merchandising machines of the prior art.

Other and further objects of our invention will appear from the following description.

In general, our invention contemplates the provision of an aperture delivery merchandising machine including a cabinet formed with a plurality of slots or apertures in which individual articles of merchandise, such as packages of cigarettes or the like, are positioned for delivery to customers, but in protected and in accessible locations. Means responsive to the deposit in the machine of a sum in coins aggregating the purchase price of an article of merchandise renders operable a plurality of dispensing mechanisms associated with the respective apertures. Selecting means permits a customer to operate one of the dispensing means to push an article of merchandise, such as a package of cigarettes, a predetermined distance through the corresponding aperture to a position where it is in view of and accessible to a customer.

In the accompanying drawings which form part of the instant specification and which are to be read in conjunction therewith and in which like reference numerals are used to indicate like parts in the various views:

Figure 1 is a perspective view of our aperture delivery merchandising machine.

Figure 2 is a fragmentary sectional view, drawn on an enlarged scale, of our aperture delivery merchandising machine, taken along the line 2-2 of Figure 1.

Figure 3 is a fragmentary sectional view, drawn on an enlarged scale, of our aperture delivery merchandising machine, taken along the line 3-3 of Figure 1.

Figure 4 is a fragmentary perspective view, with parts in section, of our aperture delivery merchandising machine.

More particularly referring now to the drawings, our aperture delivery merchandising machine includes a cabinet, indicated generally by the reference character 10, having a front 12, a back 14, sides 16, a top 18 and a base 20. The front 12 of the cabinet 10 is formed with an opening 22 in which we mount a closure panel 24. A coin slot 28 carried by the top 18 of the machine permits the insertion of coins into the coin register of the machine. The panel 24 carries a coin return lever 30 mounted in a slot 32. Coin return lever 30 may be actuated by a customer to return coins in a manner known to the art in the event the supply of merchandise of the kind he desires is exhausted. As can be seen by reference to Figures 1 and 3, the panel 24 carries a window 34 through which the articles of merchandise next to be dispensed may be viewed by a customer. Panel 24 is formed with a plurality of apertures 36 through which articles of merchandise are delivered to a customer. The number of apertures 36 corresponds to the number of sections into which the machine is divided.

Rivets 38 or the like secure a bracket 40 extending across substantially the entire width of the machine to back 14. Adjacent the front 12 of the machine between a side 16 of the machine and a bearing panel 42 arranged adjacent the other side of the machine, we mount a second bracket 44 by any convenient means. At spaced intervals along the bracket 44, we weld a number of panel mounting plates 46. Plates 46 extend forwardly of cabinet 10 to form the sides of an aperture 36. Associated with each of the apertures 36

APERTURE DELIVERY CIGARETTE MERCHANDISING MACHINE

Application April 6, 1955, Serial No. 499,588

6 Claims. (Cl. 221—131)

Our invention relates to a merchandising machine and more particularly to an aperture delivery cigarette merchandising machine which delivers an article of merchandise to a customer without the use of a conventional delivery slot and tray.

Merchandising machines of the prior art, and especially those machines which are adapted to dispense cigarettes, are each provided with an elongated slot opening into a delivery tray onto which the dispensed package of merchandise passes when the machine is operated. The customer must reach into the access opening and pick the package of merchandise out of the delivery tray. Because the supplies of merchandise and dispensing mechanism of the machine are arranged above the delivery tray, it is low on the machine. Consequently, the customer must bend over or stoop in order to reach the merchandise on the tray. Moreover, the access openings for the delivery trays of the machines of the prior art are narrow so that a package of merchandise deposited on the tray very often is out of view of the customer. As a result, in order to obtain the merchandise, the customer must sometimes grope around on the tray until he locates the package of merchandise. It will be seen that these narrow access openings and low delivery trays are an inconvenient means for delivering the merchandise to a customer. Further, since a delivery chute is employed to deliver dispensed packages of merchandise to the tray, the possibility exists that packages of merchandise may be caught in the chute, with the result that the customer does not obtain the purchased article of merchandise. Then too, the delivery chute and tray take up a certain amount of space which otherwise could be used to store merchandise.

We have invented an aperture delivery merchandising machine which does away with the delivery tray and delivery opening employed in the prior art. Our machine provides a ready, convenient and expeditious means for delivering an article of merchandise to a customer. Our machine so positions the dispensed article that it is in view of and may readily be grasped by the customer. Our machine functions in a convenient manner so that a customer may obtain a dispensed article without stooping and without groping to locate the article. Our machine also eliminates the dispensing chute customarily employed in merchandising machines of the prior art so that the possibility of an article of merchandise becoming stuck in it during delivery is minimized.

One object of our invention is to provide an aperture delivery merchandising machine which does away with the delivery tray employed in merchandising machines of the prior art.

Another object of our invention is to provide an aperture delivery merchandising machine which delivers an article of merchandise to a customer in a ready, convenient and expeditious manner.

A further object of our invention is to provide an aperture delivery merchandising machine which presents

is a pair of channel guides 48, each of which is formed with a depending flange 50. Each of the guides 48 extends from the support bracket 40 at the back of the machine to one of the plates 46 adjacent the front of the machine. Guides 48 are supported by any suitable means on the bracket 40 and on plates 46.

As can be seen by reference to Figures 3 and 4, each of the plates 46 carries a pin 52 which pivotally mounts a lug 54 fixed between a pair of panels 56. Each of the panels 56 is formed with a flange or retaining lip 58 along its forward edge. A bar 60 fixed to all of the flanges 58 provides a means by which the panels 56 may be swung as a unit about pins 52. The panels carried by a pair of adjacent plates 46 form the front column, indicated generally by the reference character 62, of a section of the machine. In order to form the rear columns of a section of the machine, we mount partitions 64 between adjacent guides 48 in alignment with the panels 56. Panels 64 carry first retaining lips 66 extending along their front edges from a point adjacent the top of the machine to a point above guides 48. Vertical flanges 68, disposed intermediate the length of panels 64, form, together with lips 66, the intermediate columns of the machine, each of which is indicated generally by the reference character 70. Retaining lips 72, secured along the rear edges of partitions 64, together with flanges 68, define the rear columns of the machine, each indicated generally by the reference character 74. It will be seen that a front column 62, an intermediate column 70 and a rear column 74 make up a section of the machine associated with an aperture 36.

Disposed below the columns of each section and carried for reciprocation in a pair of guides 48, we mount a slide 76. Each slide 76 has a forward extension 78 which supports the package 80 of merchandise next to be dispensed from the associated section in a position where it may be viewed by a customer through the window 34. A pair of ears 82 pivotally mounted a first pusher 79 on a pin 84 carried on the underside of the slide 76. A spring 86 surrounding the pin 84 bears with one end against an ear 82 and with the other end against the side of slide 76 to urge the pusher 79 in a clockwise direction as viewed in Figure 3. Each pusher 79 has an upwardly inclined portion 88 which normally extends through an opening 90 in the corresponding slide 76. Each pusher 79 is associated with the front column 62 of a respective machine section and is arranged to urge the lowermost package in this section to the left as viewed in Figure 3 when the slide 76 is operated in a manner to be described hereinafter.

The slide 76 carries a second pusher 92 which is pivotally mounted by a pair of depending ears 94 on a pin 96 carried by the slide 76. A spring 98 surrounding pin 96 bears with one end on an ear 94 and has its other end fixed in one of the sides of slide 76 to bias pusher 92 to rotate in a clockwise direction as viewed in Figure 3. Each pusher 92 has a raised portion 100 which normally extends upwardly through an opening 102 formed in the corresponding slide 76. Each pusher 92 is associated with the second column 70 of a respective machine section and is arranged to advance the bottommost package in the second column when the slide is operated.

A third or rear pusher 104, associated with the rear column 74 of each section, carries a pair of upstanding lugs 106 which pivotally mount the pusher on a pin 108 carried by the sides of slide 76. A spring 110, fixed at one end to a depending lug 112 on pusher 104 and at the other end to a lug 114 formed on the slide 76, biases pusher 104 to rotate in a clockwise direction as viewed in Figure 3. The rear, or right-hand, end of each pusher 104, as viewed in Figure 3, has an upstanding portion 116. When slide 76 moves rearwardly, or to the right as viewed in Figure 3, bracket 40

5 cams the associated pusher 104 upwardly against the action of spring 110 to engage the lowermost package in column 74 upon operation of the machine. In order to retain pusher 104 in the up position during the return stroke of slide 76, we pivotally mount a U-shaped latch 118 on the pin 96. Latch 118 has a first arm 120 for engaging a lug 122 on pusher 104 when the latter is cammed upwardly by bracket 40. A spring 124, fixed at one end to a second arm 126 of the latch 118 and at the other end to one of the sides of slide 76, normally biases latch 118 to rotate in a clockwise direction as viewed in Figure 3. When the slide 76 moves rearwardly, or to the right as viewed in Figure 3, bracket 40 cams pusher 104 upwardly against the action of spring 110 to snap lug 122 into engagement with arm 120. This action takes place against the action of spring 124. In order to disengage latch 118 to permit pusher 104 to resume the position shown in Figure 3 after a dispensing operation, we mount a latch release member 128 on the flange 50 of one of the guides 48. When slide 76 returns to the position shown in Figure 3, member 128 engages arm 126 and pivots latch 118 out of engagement with lug 122 to permit pusher 104 to return to the position shown in Figure 3.

20 A platform 130 fixed between one side 16 of the cabinet and the bearing plate 42 has a plurality of transverse depending flanges 132 adjacent the respective sections of the machine. Each of the slides 76 of the machine carries a depending finger 134 fixed by any suitable means to the underside of the slide adjacent the opening 90. Fingers 134 extend through respective openings 136 in pushers 79. The openings 136 are sufficiently long to permit pivotal movement of the pusher 79 without interference with the finger 134. Each finger 134 also passes through a slot 142 in a dispensing pusher rod 140. A spring 138, fixed 30 between finger 134 and the associated pusher rod 140, normally urges rod 140 to the left, or toward the corresponding aperture 36. Rod 140 carries a pusher 144 at its forward or left-hand end, as viewed in Figure 3.

35 From the structure thus far described, it will be appreciated that as slide 76 moves rearwardly, its forward extension 78 is retracted to drop the package 80 supported thereby onto the platform 130. The rearward movement of slide 76 carries pusher 144 rearwardly by virtue of the engagement of finger 134 with slot 142 so that package 80 drops in front of pusher 144. As the slide makes its return stroke, spring 138 acting through pusher rod 140 resiliently urges the package 80 toward the corresponding aperture 36. It will readily be appreciated that if the aperture 36 were open at this time, pusher 144 under the 40 action of spring 138 would force the package 80 directly out of the aperture so that it might fall to the floor supporting the machine.

45 In order to prevent a package being dispensed from being completely ejected through the respective openings 55 or apertures 36 during a dispensing cycle, we pivotally mount a plurality of respective shutter arms 146 by means of ears 148 on pins 150 carried by respective pairs of flanges 132 of each section. Each shutter arm 146 is formed at its forward or left end, as viewed in Figure 3, 60 with a shutter 152. A spring 154 fixed between a lug 156 on the underside of the arm 146 and a rod 158 extending between a side 16 and the panel 42 normally biases arm 146 to pivot in a counterclockwise direction as viewed in Figure 3 to move the shutter 152 clear of the aperture 36.

65 A flange 160 on shutter 152 limits the movement of arm 146 under the action of spring 154 by its engagement with the lower edge of slot 36. In order to move a selected arm 146 to position its shutter 152 to close the corresponding aperture 36 at the beginning of a dispensing cycle, we pivotally mount a selector member 162 on a pin 164 carried by ears 166 depending from the underside of the platform 130. Each selector member 162 extends downwardly through a slot 163 in the associated shutter arm 146.

70 As can be seen by reference to Figures 3 and 4, a push

button 168, associated with a section, is arranged when actuated to operate the member 162 by means of a push rod 170. We slidably mount push rod 170 in a slot 172 formed in the front 12 of the machine. When actuated, a push button 168 operates the rod 170 to push member 162 in a counterclockwise direction about its pivot 164, as viewed in Figure 3. When member 162 pivots, a cam projection 174 carried thereby engages the underside of arm 146 to cam it to close shutter 152 and thus shut the associated aperture 36. The length of slot 163 permits the pivotal movement of the associated member 162 while ensuring the engagement of projection 174 with the underside of arm 146. In order to retain shutter 152 in aperture closing position until the end of the dispensing cycle, we mount a leaf spring 176 on a rivet 178 carried by a housing 180. Housing 180 carries a locking slide assembly, indicated generally by the reference character 182, of a type well known in the art. The locking slide assembly 182 is actuated by rod 170 to prevent actuation of any other selecting button 168 when one of the buttons is operated. In the position shown in Figure 3 before a dispensing operation is initiated, the shutter 152 holds leaf spring 176 against housing 180. When a selecting button 168 is operated, rod 170 pivots member 162 in a counterclockwise direction as viewed in Figure 3 so that projection 174 moves arm 146 to close shutter 152 to shut the aperture 36. When shutter 152 has been moved to this position, spring 176 is released and permitted to move to a position where its upper end supports the shutter in aperture closing position. As will be explained in detail hereinafter, we provide means for moving spring 176 back against housing 180 to permit shutter 152 to drop to the position shown in Figure 3 at a point near the end of the dispensing cycle.

As can be seen by reference to Figures 2 and 4, each of the rods 170 passes through an opening 184 formed along the length of a starting crank 186 fixed on a shaft 188 for rotation therewith. A transverse enlargement 185 on rod 184 engages crank 186 to turn shaft 188 when a push button 168 is operated. Shaft 188 is mounted in suitable bearings on sides 16 and extends through an opening 190 in panel 42. When one of the buttons 168 is operated, member 186 and shaft 188 pivot in a clockwise direction, as viewed in Figures 2 and 4. The end of member 186 which extends through the panel 42 engages and operates a drive motor start link 192 slidably mounted by means of respective slots 194 and 196 on a pair of pins 198 and 200 carried by the panel 42. When a button 168 is operated, member 186 moves link 192 to the right, as viewed in Figure 2. A pin 204 pivotally connects the end of link 192 remote from the member 186 to a lever 202, which is pivotally mounted on a pin 206 carried by the panel 42. When start link 192 is actuated, lever 202 pivots in a clockwise direction as viewed in Figure 2, and its end remote from pin 204 engages and actuates the start button 208 of a motor start-stop switch 210. Start-stop switch 210 energizes the machine drive motor (not shown) when button 208 is operated. The drive motor drives a shaft 212 which carries a cam 214 having a heart-shaped cam track 216. One arm 218 of a bell crank, indicated generally by the reference character 220, carries a follower 222 which rides in the track 216. A pin 226 pivotally connects the other arm 224 of bell crank 220 with a link 228 connected to the operating bar 230 of the machine. A pin 221 pivotally mounts bell crank 220 on the support panel 42. The operating bar 230 is slidably mounted in a slot 232 formed in the panel 42 and in a suitable bearing means (not shown) in the side 16 remote from the panel 42. As shaft 212 rotates, the operating bar 230 of the machine reciprocates to drive the selected slide in a manner to be described hereinafter.

Shaft 212 carries for rotation with it a crank 234 pivotally connected by a pin 236 to a link 238 con-

nected by a pin 240 with an arm 242 of a bell crank pivotally mounted on pin 221. The bell crank including arm 242 has a second arm 244 pivotally connected by a pin 248 with a link 250 slidably mounted in a bracket 252 on the panel 42. The upper end of link 250, as viewed in Figure 2, carries a pin 254 adapted to engage and tilt the money dump tray or shelf (not shown) of the machine coin register. When shaft 212 is driven, it drives crank 234 in a direction to reciprocate link 250 vertically to dump the coins into the coin box. In order to stop the main drive motor when a dispensing operation is complete, we slidably mount a motor stop link 256 in a bracket 257 carried by the panel 42. One end of link 256 is engaged by a projection 258 carried on cam 214 at a point near the end of the dispensing cycle. When engaged by projection 258, link 256 moves to the right, as viewed in Figure 2, to actuate the stop button 260 of switch 210 to interrupt the motor circuit.

Referring now to Figures 3 and 4, the operating bar 230 of the machine pivotally carries at respective spaced locations along its length a plurality of selecting links 262 for movement with it. One selecting link 262 is provided for each section. The arrangement is such that before a selection is made, each of the links 262 is in the position shown in Figure 3. In this position the forward or left end 264 of the link engages and retains spring 176 in a position against housing 180. The other end of each of the links 262 is formed with a pair of bifurcations 266 and 268. Bifurcation 268 is longer than bifurcation 266. When the button 168, corresponding to a section of the machine, is actuated, the member 162 pivots in a counterclockwise direction as viewed in Figure 3. At this time a pin 270 carried by the lower end of the member 162 engages a link 262 to pivot it in a clockwise direction, as viewed in Figure 3, about operating bar 230. At the same time, the operating bar 230 moves rearwardly and the bifurcation 266 engages a pin 272 carried by the operating lever 274 of the particular section. A rod 276 extending from side to side of the machine pivotally mounts the operating lever 274 of each section. The upper end of each of the levers 274 is bifurcated and operatively engages a pin 278 carried by a depending lug 280 formed on the corresponding slide 76. When the operating bar 230 moves rearwardly, or to the right as viewed in Figure 3, the bifurcation 266 of the selected link 262 engages pin 272 to rotate the operating lever 274 about rod 276 in a clockwise direction as viewed in Figure 3. This action carries the slide 76 to the rear of the machine and also releases spring 176 so that it may support shutter 152 in aperture closing position. The engagement of bifurcation 266 with pin 272 is maintained during the rearward stroke of the slide 76. When the direction of movement of the operating bar 230 is reversed, the selected link 262 returns to the position shown in Figure 3. As the operating bar returns, bifurcation 268 engages the pin 272 to return the selected lever 274 and slide 76 to the forward position. When the operating bar is at a point near the end of its return movement, the end 264 of the selected link 262 engages spring 176 to move it from under shutter 152 and permits the shutter to return to the position shown in Figure 3 under the action of spring 154.

We pivotally mount a first baffle 282 on a pin 284 at the lower edges of the flanges 66 separating the first column 62 from the intermediate column 70 of a section. A pin 288 extending between the flanges 68 at the lower ends thereof pivotally mounts a second baffle 286 between the middle column 70 and the rear column 74. Baffles 282 and 286 prevent interference between the packages of cigarettes as the bottommost packages in each column of a selected section move forwardly during the return stroke of the slide 76, thus ensuring against possible jamming of the machine.

In the operation of our aperture delivery merchandising machine, the customer first deposits a sum in coins aggregating the purchase price of the desired article in the coin slot 28 of the machine. This deposit conditions the main drive motor circuit (not shown) to operate in a manner known to the art. The customer then pushes the selecting button 168 corresponding to the brand of merchandise desired. Actuation of such a selecting button and the rod 170 associated with it pivots the member 162 in a counterclockwise direction as viewed in Figure 3. This pivotal movement of the member 162 performs two operations. It moves the shutter 152 to the up position against the action of spring 154 to close the aperture 36 corresponding to the selected brand or type of merchandise. When member 162 rotates, its pin 270 engages the corresponding selecting link 262 to pivot it in a clockwise direction about the operating bar 230. This movement of link 262 releases spring 176 to permit it to move to a position to support the shutter 146 in aperture closing position. Pivotal movement of link 262 also positions bifurcation 266 to engage the pin 272 on the corresponding selecting lever when operating bar 230 moves rearwardly.

Actuation of a selecting button 168 pivots member 186 in a clockwise direction, as viewed in Figures 2 and 3, to move the start link 192 to the right as viewed in Figure 2. Movement of start link 192 to the right rotates lever 202 in a clockwise direction as viewed in Figure 2 about its pivot 206 to operate the start button 208 of switch 210. Operation of the start button 208 energizes the main drive motor to rotate shaft 212 in a direction to move the operating bar 230 first rearwardly and then forwardly of the machine. As the operating bar 230 moves rearwardly, the bifurcation 266 of the selected link 262 engages pin 272 to rotate lever 274 in a clockwise direction about the rod 276. As lever 274 is moved in a clockwise direction, it pulls slide 76 rearwardly, or to the right as viewed in Figure 3. As slide 76 moves to the rear, it carries the dispensing pusher 144 to the rear by virtue of the engagement of finger 134 with the rear end of slot 142. Also, as the slide 76 moves rearwardly, the package next to be dispensed is dropped to the platform 130 in front of pusher 144. When the pushers 79 and 92 are moved to the rear, their portions 88 and 100 are cammed downwardly into the respective openings 90 and 102 by the weight of the packages in columns 62 and 70. When the slide 76 reaches the end of its rearward stroke, projections 88 and 100 return to the up position under the influence of the respective springs 86 and 98. In this position pushers 79 and 92 push the respective lowermost packages in columns 62 and 70 to the left as viewed in Figure 3 on the return stroke of the slide 76. When slide 76 reaches a point near the end of its rearward stroke, portion 116 of the rear pusher 104 is engaged by bracket 40 to pivot the pusher to the up position against the action of spring 110 to position projection 116 to engage and advance the lowermost package in column 74 during the return movement of slide 76. Pusher 104 is retained in this up position by the engagement of arm 120 of latch 118 with the lug 122.

When the direction of movement of the operating bar 230 reverses, pin 272 is released from bifurcation 266 and engaged by bifurcation 268 to return lever 274 to the position shown in Figure 3. In the course of this movement, the respective pushers 79, 92 and 104 engage the lowermost packages in the columns 62, 70 and 74 to carry them forward until the parts return to the position shown in Figure 3. It will be remembered that the package 80, which was supported by the extension 78, has dropped to platform 130. The lowermost package in column 62 is now supported by extension 78. The lowermost package in column 70 has become the lowermost package in column 62, the lowermost package in column 74 has become the lowermost package in column

70, and the package next above the lowermost package in column 74 has become the lowermost package in column 74.

It will be appreciated that the package 80 which was dropped on the platform 130 in front of the pusher 144 during the rearward movement of slide 76 is urged to the left toward aperture 36 by pusher 144 acting under the influence of spring 138 during the return movement of the slide 76. At this time, however, the shutter 152 closes the aperture so that pusher 144 can only urge the package up against the shutter. Slot 142, in which finger 134 is disposed, provides lost motion between bar 140 and slide 76 so that pusher 144 may be prevented from returning to its initial position when slide 76 returns. As long as the aperture 36 remains closed, pusher 144 is spring loaded to urge the package through the aperture by virtue of the relative movement between slide 76 and bar 140. At a point near the end of the return stroke of the operating bar 230, end 264 of link 262 engages spring 176 to move it against housing 180 and out from under shutter arm 146 to permit the shutter 152 to be returned to the position shown in Figure 3 by the action of spring 154. When shutter 152 is so returned, the package which was held between the shutter 152 and the dispensing pusher 144 is urged a predetermined distance through the aperture 36 by the action of spring 138. The tension on spring 138 is so selected that the package 80 is pushed through the aperture 36 only a sufficient distance to permit the package to be observed and conveniently grasped by a customer. When the slide 76 reaches the end of its return stroke, lug 128 engages arm 126 of latch 118 to permit pusher 104 to assume the position shown in Figure 3 under the influence of spring 110. Also, at a point near the end of the dispensing operation, projection 258 actuates link 256 to operate the motor stop button 260 to de-energize the motor drive circuit. The coin acceptance link 250 is actuated to tilt the coin shelf to permit the coin or coins deposited in the coin register to fall into the coin box of the machine. Baffles 282 and 286 permit the forward movement of the lowermost packages in the columns 70 and 74 without interference with the next to lowermost packages in respective columns 62 and 70. The locking slide assembly 182 prevents operation of more than one section of the machine for a single deposit of the coins.

It will be seen that we have accomplished the object of our invention. We have provided an aperture delivery merchandising machine which does away with the delivery tray of the machines of the prior art. Our machine presents a dispensed package in a position where it is readily accessible to and may be viewed by a customer. Our machine permits more efficient utilization of available cabinet space in the machine since no delivery chute nor delivery tray are employed. Our machine is provided with means for preventing the complete ejection or projection of a dispensed package from a machine. Our machine dispenses merchandise in an extremely convenient manner so that a customer need not stoop over or grope around in a delivery opening to obtain a dispensed article.

It will be understood that certain features and sub-combinations are of utility and may be employed without reference to other features and sub-combinations. This is contemplated by and is within the scope of our claims. It is further obvious that various changes may be made in details within the scope of our claims without departing from the spirit of our invention. It is therefore to be understood that our invention is not to be limited to the specific details shown and described.

Having thus described our invention, what we claim is:

1. A merchandising machine including in combination a cabinet formed with a plurality of apertures, a plurality of columns formed in said cabinet for containing articles of merchandise to be dispensed, said columns being as-

sociated respectively with said apertures, a plurality of dispensing means associated with the respective columns, each of said dispensing means adapted when operated to advance an article of merchandise toward its associated aperture, drive means for said dispensing means, means for selectively coupling said drive means with one of said dispensing means, first means responsive to the operation of a selecting means to energize said drive means after it has been conditioned to operate, and second means responsive to the operation of a selecting means for controlling the operation of the associated dispensing means whereby a dispensed article is pushed partially through said aperture.

2. A merchandising machine as in claim 1 in which said drive means drives a coupled dispensing means with a rearward and a forward stroke, each of said dispensing means including a platform, a pusher mounted for sliding movement on said platform, means operated by said drive means for dropping an article to be dispensed between said pusher and the associated aperture during said rearward stroke, means carried by said drive means operated means for moving said pusher rearwardly during a portion of the rearward stroke, and a resilient connection between said drive means operated means and said pusher, the arrangement being such that a dropped article is resiliently urged toward said associated aperture during said forward stroke.

3. A merchandising machine as in claim 1 in which each of said means for controlling the operation of the dispensing means includes a shutter normally disposed in a position clear of the associated aperture, means responsive to the operation of a selecting means for moving the corresponding shutter to a position to close the associated aperture at the beginning of a dispensing operation, means for retaining said shutter in a position to close the associated aperture during a major portion of the dispensing operation, and means responsive to said drive means for releasing said retaining means at a point near the end of said dispensing operation.

4. A merchandising machine as in claim 1 wherein each of said dispensing means includes a platform, a slide, means mounting said slide for reciprocating movement below said column, said slide being formed with a forward extension for supporting an article of merchandise over said platform, means operatively connected to said slide and adapted to be coupled with said drive means upon operation of the associated selecting means, a dispensing pusher mounted for sliding movement on said platform, a resilient connection between said slide and said pusher, said drive means driving a coupled slide with a rearward and a forward stroke, means carried by said slide for engagement with said pusher during a portion of said rearward stroke, the arrangement being such that the article carried by said forward extension is dropped in front of said pusher during said rearward stroke, said resilient connection providing means for resiliently urging said dropped package toward said aperture on the forward stroke, and means carried by said slide for retaining a package from said column on said forward extension during said forward stroke.

5. A merchandising machine as in claim 1 in which said drive means drives a coupled dispensing means with a rearward and a forward stroke, each of said dispensing means including a platform, a pusher mounted for sliding

65

movement on said platform, means operated by said drive means for dropping an article to be dispensed between said pusher and the associated aperture during said rearward stroke, means carried by said drive means operated means for moving said pusher rearwardly during a portion of the rearward stroke, and a resilient connection between said drive means operated means and said pusher, the arrangement being such that a dropped article is resiliently urged toward said associated aperture during said forward stroke, each of said means for controlling the operation of the dispensing means includes a shutter normally disposed in a position clear of the associated aperture, means responsive to the operation of the selecting means for moving said shutter to a position to close the associated aperture at the beginning of a dispensing operation, means for retaining said shutter in a position to close the associated aperture during a major portion of the dispensing operation, and means responsive to said drive means for releasing said retaining means at a point near the end of said dispensing operation.

6. A merchandising machine for dispensing articles of merchandise including in combination a cabinet formed with an aperture, a column formed in said cabinet for containing articles of merchandise to be dispensed, dispensing means for advancing an article of merchandise from said column toward said aperture, said dispensing means including a resilient connection, drive means for said dispensing means, means for energizing said drive means and coupling the drive means with the dispensing means, and means responsive to the operation of said energizing means for controlling the operation of said dispensing means whereby said dispensing means pushes a dispensed article partially through said aperture, said means for controlling the dispensing means including a closure member for said aperture, means urging said closure member to close said aperture at the beginning of a dispensing operation, means for retaining said closure member in a position closing said aperture during a major portion of the dispensing operation whereby said resilient connection resiliently urges the article being dispensed against said closure member, and means responsive to said drive means for releasing said retaining means at a point near the end of a dispensing operation to permit the dispensed package to be pushed partially through said aperture under the action of the resilient connection after the closure member has been released by the retaining means.
